UNITED STATES PATENT OFFICE.

THOMAS H. STOKES, OF LINCOLN, ILLINOIS.

GROUNDING-SHOE FOR ELECTRIC WIRES.

SPECIFICATION forming part of Letters Patent No. 642,169, dated January 30, 1900.

Application filed June 12, 1899. Serial No. 720,312. (No model.)

To all whom it may concern:

Be it known that I, THOMAS H. STOKES, of Lincoln, in the county of Logan and State of Illinois, have invented a new and Improved 5 Grounding-Shoe for Electric Wires, of which the following is a full, clear, and exact description.

This invention relates to devices for grounding telephone, telegraph, or other electric 10 wires; and the object is to provide a simple and comparatively inexpensive device by the use of which the end of a wire may be quickly and easily grounded without first digging a hole in the ground.

15 I will describe a grounding-shoe for electric wires embodying my invention and then point out the novel features in the appended claims.

Reference is to be had to the accompanying 20 drawings, forming a part of this specification, in which similar characters of reference indicate corresponding parts in both the figures.

Figure 1 is a sectional view of a grounding-shoe embodying my invention and showing 25 the same in use, and Fig. 2 is a perspective view of the shoe.

Referring to the drawings, 1 designates the shoe, made of any suitable material—such, for instance, as wood or metal—copper or brass 30 being preferable.

The shoe is pointed at its lower end, so that it may be easily forced into the ground, and at its upper portion it has a recess or socket 2, into which the end of an iron rod or other 35 suitable instrument (shown in dotted lines in Fig. 1) may be inserted for forcing the device into the ground: It may be here stated that the iron rod should fit loosely in the socket, so that it may be withdrawn without 40 drawing the shoe up with it and to avoid friction with the ground in being driven down.

At one side the shoe has a longitudinal channel 3, and at the opposite side it has a

recess 4, and a transverse hole 5 connects the channel with the recess. In use the wire α 45 is to be inserted through the hole 5, a portion of the wire resting in the channel 3 and the end of the wire being turned into the recess 4. The channel 3 and recess 4 are sufficiently deep to permit the wire to be seated wholly 50 within the circumference of the shoe, so that there are no outside projections that would interfere with the movement of the device into the ground. When the device is to be inserted into the ground, the iron rod or similar instrument is to be inserted in the socket 2, and then by forcing the rod downward the shoe will be pushed into the ground, after 55 which the rod is to be withdrawn and the hole filled up above the shoe. 60

Having thus fully described my invention, I claim as new and desire to secure by Letters Patent—

1. A grounding device for an electric wire, comprising a shoe sharpened at its lower end 65 and having a transverse hole for receiving a grounding-wire, substantially as specified.

2. A grounding device for an electric wire, comprising a shoe pointed at its lower end, the said shoe having a longitudinal channel 70 at one side, a recess at the other side, and a hole connecting the recess and the channel, substantially as specified.

3. A grounding device for an electric wire, comprising a shoe having a sharpened or 75 pointed end, and having a socket at its upper portion, the said shoe also having at one side a longitudinal channel and at the opposite side a recess, and a transverse hole connecting the recess and channel, substantially 80 as specified.

THOMAS H. STOKES.
